UNITED STATES PATENT OFFICE.

ISAAC NEWTON DICKINSON, OF READING, PENNSYLVANIA, ASSIGNOR TO
THE PENNSYLVANIA IRON WORKS, OF SAME PLACE.

GRATE-BAR.

SPECIFICATION forming part of Letters Patent No. 378,195, dated February 21, 1888.

Application filed June 23, 1887. Serial No. 242,211. (Model.)

To all whom it may concern:

Be it known that I, ISAAC NEWTON DICKINSON, of Reading, county of Berks, and State of Pennsylvania, have invented an Improvement 5 in Grate-Bars, of which the following is a specification.

My invention has reference to grate-bars; and it consists in certain improvements, all of which are fully set forth in the following specification and shown in the accompanying drawings, which form part thereof.

The object of my invention is to so form a grate-bar that when in use the air-currents will be properly guided upward to the fire, the 15 draft being automatically equalized over the entire surface of the grate-bar.

My object is also to so form the bar that the strains due to expansion and contraction will be equalized, avoiding warping and insuring 20 long service.

In addition to the above my object is to obtain a large area for the admission of air through the grate.

In carrying out my invention I form the 25 grate-bar with two longitudinal parallel side webs having a series of oblique cross-webs cast between them, and between which are the air-passages in the top of the bar, which are made rectangular or parallelogrammic in area, 30 and made oblique, as in the case of the cross-webs. The sides of the bar have lugs, which prevent the next or adjacent bar being placed so close as to prevent the free passage of air. The longitudinal webs are desirably made serpentine to allow the ready equalizing of the 35 air-currents under all of the bars.

In the drawings, Figure 1 is a plan view of a grate-bar embodying my invention. Fig. 2 is a side elevation of same with part in section, 40 and Fig. 3 is a cross-section on line *x-x*.

A is the upper or body part of the grate-bar, and is made flat upon the top and perforated by holes or air-passages D, made oblong, rectangular, or parallelogrammic, so as to give a 45 large area. The bar is made very wide, so that but a few bars are required to a large furnace, and are therefore easily kept clean. The bars are provided with the two longitudinal side webs, B B, which extend downward to 50 strengthen them.

Care downwardly-extending cross-webs cast solid with the side webs, B, and are arranged at an angle, so as to form oblique divisions, the lower ends pointing toward the front of the furnace, so as to catch incoming drafts of 55 air and direct them upward. The openings D in the grate-bars are also oblique, corresponding with the webs C, and the lower parts thereof at *d* are made wider than the top, so as to allow any ashes, cinders, &c., which may 60 enter at the top to fall freely out at the bottom. The webs Care of substantially the same depth, and the side webs, B, are preferably notched, as at *b*, between the webs C, so as to allow a lateral circulation of any excess of 65 air which may pass under a grate-bar, and thus supply another bar with an equal draft.

The peculiar construction here set out will prevent warping of the bar, as the strains will be equally distributed over it. The great 70 depth possible in the upper or body portion of the bar enables the casting between the air-passages D to be very thin, and thus increase the proportional air-area when compared to the solid portion, and by the depth of these 75 divisions in the body portion the air-currents are readily guided upward, as in the case of the webs C.

The sides of the bars are provided with lugs E, which prevent two adjacent bars coming in 80 close contact, (see dotted lines, Fig. 1,) and thus insure intermediate air-passages, and these lugs E are also made oblique, so as to direct the air upward, as in the case of the webs C.

It is evident that the details may be somewhat modified without departing from my invention.

Having now described my invention, what I claim as new, and desire to secure by Letters 90 Patent, is—

1. A grate-bar wherein there are two deep side webs parallel to each other, having cast thereto a series of shallow oblique cross-webs, forming air-spaces which are rectangular parallelogram in form and increase in area as they are removed from the surface of the bar, and deep cross-webs arranged at intervals apart and including between two such deep cross-webs a series of shallow cross-webs, the 95 100

said deep oblique webs having the same direction of obliquity as the shallow webs and extending considerably below said shallow webs.

2. A grate-bar having a flat top and two deep side webs having serrated lower edges, the top being perforated between the said webs, forming oblique air-passages, which increase as they are removed from the surface of the bar.

In testimony of which invention I hereunto set my hand.

ISAAC NEWTON DICKINSON.
